DOOR LOCK

Peter F. Rossmann, Detroit, Mich., assignor to
 Packard Motor Car Company, Detroit, Mich., a
 corporation of Michigan

Application December 5, 1936, Serial No. 114,383

14 Claims. (Cl. 70—264)

This invention relates to door securing means and more particularly to mechanism for securing motor vehicle doors.

In conventional door securing mechanism for motor vehicles of the sedan body type there is a latch mechanism for each door controlled by a handle on the outside and by another handle on the inside. Usually there is mechanism for locking the doors from the interior of the body consisting of individually operable mechanism for each door, or a mechanism on each side of the body operable to lock both doors on the same side therewith. There is also key operable mechanism for locking one of the doors from the outside, usually the right hand door.

It is an object of this invention to provide for the locking of a door latch from either the interior or the exterior of a motor vehicle body.

Another object of the invention is to provide locking mechanism for two doors on the same side of a motor vehicle body that can be controlled either from the inside or the outside of the body.

Another object of the invention is to provide mechanism for locking the rear door and the latch of the front door of a motor vehicle body by the inside handle of the front door.

A further object of the invention is to provide a door locking mechanism that can be manually actuated from the inside of the motor vehicle body and key-tripped from the exterior of the motor vehicle body to operate automatically.

Still another object of the invention is to provide mechanism operable from the interior or the exterior of a motor vehicle body for locking a front door latch bolt and a rear door locking bolt.

Other objects of the invention will appear from the following description taken in connection with the drawings, which form a part of this specification, and in which:

Fig. 1 is a horizontal sectional view through a fragment of one side of a motor vehicle body having my invention incorporated therewith;

Fig. 2 is a fragmentary vertical sectional view of the same looking at the right hand side of the vehicle body from the interior;

Fig. 3 is a sectional view taken substantially on line 3—3 of Fig. 2;

Fig. 4 is a sectional view taken substantially on line 4—4 of Fig. 3 with the rear door locking mechanism in key-locked position;

Fig. 5 is a sectional view similar to Fig. 4, showing the rear door locking mechanism in released position;

Fig. 6 is a fragmentary sectional view taken on line 6—6 of Fig. 3;

Fig. 7 is another fragmentary sectional view taken on line 7—7 of Fig. 3;

Fig. 8 is an exploded perspective view of the major portions of the securing mechanisms for the doors.

The door securing means forming the subject matter of this invention is shown associated with a motor vehicle sedan body of conventional type, the front side wall of which is indicated at 10 and the central pillar of which is indicated at 11. In advance of and behind the central pillar 11 are openings for receiving the front door 12 and the rear door 13, the front door being hinged at its forward end, as indicated at 14, to the vehicle body and the rear door being hinged at its rear end to the body in the same manner as indicated at 14. These doors are preferably formed of sheet metal and include an outer panel 15, an inner panel 16 and marginal walls 17 extending between the panels. These doors are of conventional design.

On the forward wall of the center pillar is fixed a front door striker plate 20 and on the rear wall of this same pillar is fixed a rear door striker plate 21, the front door being provided with a sliding latch bolt 22 arranged to cooperate with plate 20 and the rear door being provided with a sliding bolt 23 arranged to cooperate with plate 21. These sliding bolts provide latches for securing the doors in closed position by means of their projection with the detents in plates 20 and 21 and the bolts can be released by mechanism operated by handles 24 arranged on the exterior of the doors. The front handle is fixed to hollow shaft 25 extending through the outer door panel 15 and fixed on such shaft is a cam lever 26 arranged to engage a leg 27 depending from the sliding bolt 22. A coil spring 28 is fixed at one end to a support 29 carried by the door and its other end engages the sliding bolt to normally move it into latching engagement with its striker plate on the central pillar. When the handle 24 is released the door can be slammed and the spring pressed sliding latch bolt will ride over its striker plate until it seats in the inner recess therein, as shown in Fig. 2, whereupon the door cannot be opened unless the sliding bolt is manually released either by turning the outside handle 24 or the inside handle 30.

Any suitable form of conventional mechanism (not shown) can be associated with the rear door to be actuated by the shaft 25 and an interior handle (not shown) for withdrawing the rear bolt 23 from latching engagement with its striker plate.

Slidably mounted in the center pillar 11 is a locking bolt 31 on which is fixed a pin 32 engaged by one end of the spring 33. The other end of this spring is fixed to a pin anchor 34 mounted in the 5 pillar. This spring normally functions to move the locking bolt in a direction toward the front door and such bolt is actuated to engage a striker plate 35 fixed to the rear door directly below the bolt 23. When the locking bolt 31 is moved 10 against the action of the spring 33 it will engage the detent in the striker plate 35 and lock the rear door with the center pillar. When the locking bolt 31 is released from its striker plate then it lies in a relation between the front and rear 15 doors such that it will not interfere with the normal door opening and closing movements.

The locking bolt 31 can be shot into locking relation with its striker plate by means of actuator mechanism consisting of a pair of slidably mounted 20 elements 36 and 37 and a spring 38. The spring is suitably mounted in a fixed relation upon the door and in a vertical plane slightly above the element 37 and engages such element to normally urge it rearwardly. The spring 38 is 25 stronger than the spring 33 so that when the actuator mechanism is released it will move the elements 37 and 36 in a direction to automatically shoot the locking bolt 31 into engagement with the striker plate 35. The element 36 when moved 30 to engage bolt 31 with the striker plate 35 extends past the inner end of the striker plate 20, see Fig. 4, and thus also serves to lock the front door with the pillar.

Associated with the actuator mechanism for 35 the locking bolt 31 is trigger means by which the mechanism can be released to shoot the bolt into locking position with the rear door, or to set the same in ineffective relation. This trigger means consists of a dog 39 pivotally mounted on a shaft 40 fixed to the door and a spring 41 fixed at 42 to the door. The spring 41 is associated with one end of the dog 39 and the dog is related with the actuator mechanism so that the spring engaged end of the dog normally lies behind the actuator 45 member 37 to hold the actuator mechanism in ineffective bolt shooting position. When the trigger is tripped so that it is moved to clear the end of the actuator element 37 then, of course, the spring 38 is free to force the elements 37 and 36 50 rearwardly thereby shooting the locking bolt 31 into locking relation with the striker plate 35 on the rear door.

The trigger can be released or set from the interior of the vehicle body or from the exterior 55 thereof. Extending axially through the hollow handle shaft 25 is a shaft 43 and this shaft projects through the handle shank and is adapted to be engaged and oscillated by a key, as indicated at 44. On the inner end of this shaft is 60 formed an eccentrically mounted pin 45 which projects into a slot 46 formed in a plunger 47. This plunger is arranged to slide in a radial slot in the handle shaft 25 in a relation such that it can be projected from the handle shaft or encased therein upon oscillation of the shaft 43. This plunger 47 is associated with the dog 39 in 65 a relation to rock the same so that the dog will clear the bottom of the bolt actuator member 37 and thereby release the same to allow the spring 70 38 to function in shooting the locking bolt 31 into locked position. Thus when the plunger 47 is moved outwardly of the shaft 25 by operation of the key 44 turning the shaft 43 and the eccentric on the end thereof, the trigger is tripped to allow

the spring 38 to shoot the locking bolt 31 into locked relation with the rear door.

When the front door is closed the spring 28 forces the sliding bolt 22 into engagement with its striker plate 20 to latch the door in closed 5 position. Turning of the key to move the plunger 47 outwardly of shaft 25 releases the trigger 39 from the actuating mechanism for locking bolt 31 causing a portion of the plunger to enter a recess 48 formed in a plate 49 fixed to a flange 75 on 10 the door. This engagement of the plunger with the recess will prevent turning of the shaft 25 by means of the exterior handle 24 so that the cam element 26 cannot be turned to release the latch bolt 22 from its striker plate. Thus the 15 front and rear doors will be locked when the key 44 is turned in a direction to move the plunger 47 radially from the shaft 25. To unlock the doors, when secured from the exterior of the body, the key 44 is inserted in the handle 24 and is 20 turned to rotate the shaft 43 in a direction moving the plunger 47 back into the shaft 25 so that it clears the recess 48 in the plate 49 and allows turning of the handle 24 to unlatch the bolt 22 from its striker plate 20 through turning of the 25 cam 26. The front end of the latch bolt 22 engages a pin 51 on the actuator mechanism element 36 when the handle is turned to release the bolt 22 from its striker and this engagement of the pin 51 moves the element 36 therewith in its 30 releasing, that is forward movement. At the same time the actuator element 36 moves the actuator element 37 forwardly against the action of the spring 38 to a position where spring 41 will force the trigger element 39 into engagement with the 35 rear end of the member 37. In this manner the actuator mechanism for the locking bolt 31 is reset into ineffective position and the spring 33 has sufficient strength to move the bolt 31 out of locking relation with its striker plate thus un- 40 locking the rear door.

The actuator mechanism for the locking bolt 31 and locking of the latch bolt 22 can also be controlled from the interior of the vehicle body and by manipulation of the handle 30. On such handle is fixed a shaft 52 that extends through and is mounted upon the inner panel wall of the door and is fixed to a lever 53 in a relation to rock the same. To this lever 53 is pivotally connected a rearwardly extending remote control 50 bar 54 having a pair of slots 55 and 56 adjacent its rear end and a depending turned-over flange portion 57. A pin 58 on the inner face of the latch bolt 22 extends through the slot 55 and a pin 59 on the inner face of the actuator member 55 36 extends through the slot 56. When the handle 30 is in normal position, as shown in the central position in dotted lines in Fig. 2, the pin 58 will be at the rear end of slot 55 and pin 59 will be at the forward end of slot 56. When the handle 30 is thrown upwardly from normal position to locking position, as indicated in full lines in Fig. 2, the lever 53 will be rocked rearwardly and will move the remote control bar 54 in a rearward direction which will move the pin 59 and the actuator element 36 in a rearward direction moving the locking bolt 31 into locking relation with its striker plate 35 on the rear door. At the same time the flange 57 will be moved under an extension 60 on the actuator element 26 which is fixed to the handle shaft 25 and will prevent rotation of the element 26 and the shaft 25. The shaft 25 cannot, under such circumstance, be rotated by the handle 24 because of this locking arrangement between the flange 57 75

and the extension 60 so that the sliding latch 22 will be locked against operation from the exterior of the vehicle body and at the same time the locking bolt 31 will be moved into position locking the rear door. Under such condition the actuator member 37 remains in set position with the trigger 39 behind the rear end thereof so that this mechanism will not require resetting when the door securing mechanism is controlled from the interior of the vehicle body.

In order to unlock the front and rear doors when the interior control has been set, the handle 30 is moved down to normal position and this will move the remote control bar 54 forwardly releasing the locking flange 57 from the extension 60 and allowing the spring 33 to move the locking bolt 31 and the element 36 forwardly to a position where the locking bolt 31 clears the plate 35 and the element 36 abuts the rear end of the actuator element 37. The handle 24 can now be turned to actuate the latch bolt 22 for opening or closing the front door and of course the corresponding handle on the rear door can be operated to open and close the rear door. The lever 53 is formed with a detent 61 which is engaged by a spring 62 suitably fixed to the front door when the handle 30 is thrown to its uppermost or locked position. This spring 62 will prevent displacement of the remote bar from locked position unless a predetermined manual pressure is applied in a direction to move the handle 30 downwardly.

The handle 30 can also be utilized to open the front door from the interior of the vehicle body by swinging the handle downwardly from normal position as indicated in dotted lines in Fig. 2. In such event the lever 53 is swung forwardly moving the remote control bar 54 therewith, and as the pin 58 lies in the rear end of the slot 55 when the handle 30 is in normal position, this downward movement of the handle and forward movement of the remote control bar 54 will cause the bar to pull the pin 58 forwardly therewith and thus release the latch bolt 22 from its striker plate so that it will clear the same and allow the door to be opened.

A housing consisting of an inside plate 70 and an outside plate 71 supports the securing mechanism within the front door panels. Plate 70 is secured to the inner panel by screws 72 and plate 71 is secured to the rear panel by screws 73, the plates being fixed together along their adjacent edges in a suitable manner. Flanges 74 struck in from the turned in rear end of the outer plate serve as a bearing for the sliding bolt 22 and the actuator member 36 and flanges 75 struck in from the outer plate support the member 36. Flanges 76 struck in from the outer plate support the actuator member 37. A struck-in flange 77 of the outer plate anchors the spring 38 and a similar flange 42 anchors the spring 41. The shaft 40 is also fixed to the outer plate of the housing.

The handle 25 passes through an escutcheon 78 which is secured to the outer panel by screws 79. To prevent axial displacement of shaft 25, the inner end extends through the housing plate and a cap screw 80 is screwed into the end thereof.

With the securing mechanism herein described, the sliding latch bolt of the front door can be locked in engagement with its striker plate either by the operation of the inside handle or by operation of a key exteriorly of the body. The rear door can also be locked simultaneously with the

front door bolt latch by operation of the inside handle or by operation of a key exteriorly of the body. Such securing mechanism can be readily reached and easily operated from the front seat when within the vehicle body or by turning a key in the front door handle when exterior of the vehicle body.

Although the invention has been described in connection with a specific embodiment, the principles involved are susceptible of numerous other applications which will readily occur to persons skilled in the art.

What is claimed is:

1. In a vehicle body having a pair of hinged doors and an intermediate pillar, a locking device comprising a locking bolt slidably mounted in the pillar and operable to lock a first door, a spring arranged to move said bolt out of door locking relation, slidable actuator mechanism on the second door for moving the bolt into locked position including a pair of aligned members and a spring urging the remote member toward bolt locking position, said last mentioned spring exerting a greater force than the first mentioned spring, a trigger engaging the actuator member remote from the bolt for holding it in ineffective position, means extending to the exterior side of the second door for tripping said trigger and allowing said actuator mechanism to shoot said bolt into locking position, and means operable from the exterior side of said door for resetting said actuator mechanism into ineffective position.

2. In a vehicle body having a pair of hinged doors and an intermediate pillar, a locking device comprising a locking bolt slidably mounted in the pillar and operable to lock a first door, a spring normally urging said bolt away from locking position, spring actuated mechanism on a second door for shooting said bolt into locking position, trigger means for holding said mechanism in ineffective relation, means for tripping said trigger to release said mechanism, and means for resetting said mechanism and trigger into ineffective position.

3. In a vehicle body having a pair of hinged doors and an intermediate pillar, a locking device comprising a locking bolt slidably mounted in the pillar and operable to lock a first door, a spring normally urging said bolt out of door locking relation, slidable actuator mechanism on a second door for shooting the bolt into door locking position, said mechanism including two aligned slidable members and a spring for actuating the member remote from the bolt, a pivoted trigger engaging the end of the spring engaged member adjacent the bolt, a spring normally urging the trigger into set position with the end of said spring engaged member, means for rocking said trigger to clear the end of said spring pressed actuator member, and means for returning said actuator mechanism into position where the trigger again engages the end of said spring pressed member.

4. In a vehicle body having a pair of hinged doors and an intermediate pillar, a locking device comprising a locking bolt slidably mounted in the pillar and operable to lock a first door, a spring normally urging said bolt out of door locking relation, slidable actuator mechanism on a second door for shooting the bolt into door locking position, said mechanism including two aligned slidable members and a spring for actuating the member remote from the bolt, a pivoted trigger engaging the end of the spring engaged member.

adjacent the bolt, a spring normally urging the trigger into set position at the end of said spring engaged member, means for rocking said trigger from the exterior of the body to clear the end of 5 said spring pressed actuator member, means for returning said actuator mechanism into position where the trigger again engages the end of said spring member, and means operable from the interior of the body for sliding the member of 10 the actuator mechanism adjacent the bolt to lock and release the bolt without disturbing the other slidable member of said actuator mechanism in its set position.

5. In a vehicle body having a pair of hinged 15 doors and an intermediate pillar, a locking device comprising a locking bolt slidably mounted in the pillar and operable to lock one of the doors, a spring normally urging said bolt out of door locking relation, slidable actuator mechanism on 20 the other door for shooting the bolt into door locking position, said mechanism including two aligned slidable members and an actuating spring engaging the member remote from the bolt, a spring closed latch bolt on the door carrying the 25 actuator mechanism, means operable to release said latch bolt, and means operable from the interior of the body for sliding the member of said actuator mechanism adjacent the locking bolt to lock and release such bolt, said means 30 operable from within the body locking said latch bolt releasing means from releasing movement when the locking bolt is moved to locking position.

6. In a vehicle body having a pair of hinged 35 doors and an intermediate pillar, a locking device comprising a locking bolt slidably mounted in the pillar and operable to lock one of the doors, a spring normally urging said bolt out of door locking position, slidable actuator mechanism on 40 the other door for shooting the bolt into door locking position, said mechanism including two aligned slidable members and a spring for engaging and actuating the member remote from the bolt, a pin on a side of the member of the 45 actuator mechanism adjacent the bolt, a trigger engaging the end of the spring engaged member of the actuator mechanism, a spring normally urging the trigger into set position with the end of the spring engaged member of the actuator mechanism, a latch bolt above the sliding member of the actuator mechanism adjacent the locking bolt having a pin on its side above the first mentioned pin, means for releasing said latch bolt, a bar 50 having slots therein through which said pins extend, means on said bar for locking said latch bolt releasing mechanism, and handle operated means for moving said bar back and forth, said bar in one portion of the handle movement moving the sliding member of the actuator mechanism adjacent the locking bolt in position locking such bolt and at the same time locking said latch bolt releasing means, said bar in another portion of said handle movement unlocking the latch bolt operating means and moving the actuator member away from the locking bolt, and said bar in another portion of said handle movement moving said latch bolt into unlatched position.

7. In a vehicle body having a pair of hinged 70 doors and an intermediate pillar, a locking device comprising a locking bolt slidably mounted in the pillar and operable to lock one of the doors, a spring normally urging said bolt out of locking position, slidable actuator mechanism on the other door for shooting the bolt into door locking position, said mechanism including two aligned 75

slidable members and a spring for engaging and actuating the member remote from the bolt, a pin on a side of the member of the actuator mechanism adjacent the bolt, a trigger engaging the end of the spring engaged member of the actuator mechanism, a spring normally urging the trigger into set position with the end of the spring engaged member of the actuator mechanism, a latch bolt above the sliding member of the actuator mechanism having a pin on its side above the first mentioned pin, a bar having slots therein through which said pins extend, means on said bar for locking said latch bolt releasing mechanism, handle operated means for moving said bar back and forth, and spring retainer means for holding said bar in position locking the locking bolt and the latch bolt operating mechanism.

8. In a vehicle body having a pair of hinged doors and an intermediate pillar, a locking device comprising a locking bolt slidably mounted in the pillar for locking one of the doors and spring pressed to unlocked position normally, slidable actuator mechanism on the other door for shooting the bolt into door locking position, said actuator mechanism including two aligned slidable 25 members and a spring for urging the member remote from the bolt in a direction to lock the same, a pivoted trigger engaging the end of the spring engaged member nearest the bolt to hold the same out of bolt operating relation, a spring 30 normally urging the trigger into set position at the end of said spring pressed member, a latch bolt on the door carrying the actuator mechanism, a spring for urging said latch bolt into latching position, a rock shaft extending to the 35 exterior of the door having a lever fixed thereon for releasing the latch bolt, a key operated shaft in said rock shaft, and means movable radially through the rock shaft and operated by the shaft therein for tripping said trigger to release said actuator mechanism and for locking said rock shaft against rotation.

9. In a vehicle body having a pair of hinged doors and an intermediate pillar, a locking device comprising a locking bolt slidably mounted in the pillar adapted to normally lock one of the doors, slidable actuator mechanism on the other door including two aligned slidable members and a spring for urging the member remote from the bolt into locking position, a pivoted trigger engaging the member remote from the bolt to hold the same out of bolt operating relation, a spring normally urging the trigger into set position with said spring pressed member, a latch bolt on the door carrying the actuator mechanism, a spring for urging said latch bolt into latching position, a rock shaft extending to the exterior of the door carrying the actuator mechanism having a lever fixed thereon for releasing the latch bolt, a key operated shaft in said rock shaft, means movable radially through the rock shaft and operated by the shaft therein for tripping said trigger to release said actuator mechanism and for locking said rock shaft against rotation, and means associated with said latch bolt for returning said actuator mechanism into position where the trigger will hold the same in reset position.

10. In a vehicle body having a pair of hinged doors and an intermediate pillar, a locking device for one of the doors comprising a spring released 70 slidable locking bolt mounted in the pillar, slidable actuator mechanism on the other door for shooting the bolt into door locking position, said mechanism including two aligned slidable members and a spring for engaging and actuating the 75

member remote from the bolt, a trigger engaging the end of the spring engaged member of the actuator mechanism to normally hold it in ineffective shooting position, a slidable latch bolt carried by the door on which the actuator mechanism is mounted, a hollow shaft extending into the door having a handle on the exterior end thereof and a lever for engaging said slidable latch bolt to move the same out of latching position, 10 a key operated shaft in the rock shaft, means operated by said key operated shaft for tripping said trigger to release said actuator mechanism and for simultaneously locking said rock shaft, means on said latch bolt for returning said actuator mechanism to set position upon operation of the hollow shaft and release of the means operated by the shaft with the hollow shaft locking said rock shaft, a bar operable from within the door carrying the actuator mechanism 15 for sliding the member of the actuator mechanism to lock the locking bolt, and a locking member carried by said bar for locking and releasing said rock shaft in accordance with the position of the actuator mechanism.

11. A locking device for vehicle doors comprising a sliding locking bolt, spring pressed means associated to move said bolt into locking position, means for retaining said spring pressed means in ineffective position, means for releasing said 20 retainer means, and actuator means for shifting said bolt into and out of locking position without disturbing the spring pressed means and its retaining means.

12. A locking device for vehicle doors comprising a sliding locking bolt having a pin thereon, a spring pressed means associated to move said bolt into locking position, means for retaining said spring pressed means in ineffective position 5 for releasing said retaining means, and actuator means engageable with the pin on said bolt for shifting said bolt into and out of locking position without disturbing the spring pressed means and its retaining means. 10

13. A locking mechanism for a vehicle door comprising a locking bolt slidably mounted to engage and lock the door, spring pressed means exerting pressure to normally release said bolt from locking engagement with the door, a latch bolt 15 for latching the door, spring means exerting pressure to normally move said latch bolt into latching position with the door, and an element operable to move said locking bolt into locking position with the door or to move said latch bolt 20 out of latching position with the door.

14. A device for locking a door to a stationary element of a vehicle comprising spring actuated locking bolt means for locking the door, means engaging said bolt means for holding the same 25 out of locking relation with the vehicle element, and a release means operable to move said bolt engaging means out of engagement with said bolt means, said release means engaging said door in a fixed relation when positioned to release said 30 bolt engaging means.

PETER F. ROSSMANN.
